(57) **CLAIM**

The ornamental design for a device for dispensing a cryogenic fluid, as shown and described.

DESCRIPTION

This design patent application is related to application Ser. No. 12/974,430, filed on Dec. 21, 2010, which is a continuation-in-part application of U.S. patent application Ser. No. 12/489,875, entitled Devices and Methods for Dispensing a Cryogenic Fluid, filed on Jun. 23, 2009. The entire contents of these related applications are incorporated herein by reference.

FIG. 1 is an isometric view of a top, front, and a right side of an exemplary embodiment of a device for dispensing a cryogenic fluid in accordance with our new design;

FIG. 2 is a top plan view of the device for dispensing a cryogenic fluid of FIG. 1; and,

FIG. 3 is a side elevational view of a right side of the device for dispensing a cryogenic fluid of FIG. 1.
